UNITED STATES PATENT OFFICE.

WILLIAM O. PECK, OF BELGRADE, NEBRASKA.

LIFTER.

1,035,728.

Specification of Letters Patent. Patented Aug. 13, 1912.

Application filed January 21, 1911. Serial No. 603,964.

To all whom it may concern:

Be it known that I, WILLIAM O. PECK, a citizen of the United States, residing at Belgrade, in the county of Nance and State 5 of Nebraska, have invented a new and useful Lifter; and I do hereby declare the following to be a full, clear, and exact description of the invention, such as will enable others skilled in the art to which it appertains to make and use the same.

This invention relates to a new and useful grappling device, and the principal object of the invention is to provide a simple, durable and efficient device of this character, 15 in which novel features are involved.

A further object of the invention is to provide a grappling device comprising a pair of extensible members, which may be so adjusted, as to permit the grappling 20 members to receive various boxes or other commodities of different dimensions.

Another feature of the invention is to arrange the grappling members in such wise as to firmly hold an article while being lifted or elevated.

It is perfectly apparent that as the commodity increases in weight, the gripping action is correspondingly increased, because of the arrangement of the grappling member. Furthermore, it is clearly evident that 30 the grappling members may be adjusted, as to fit within a box or an opening of any other commodity, so that the same may be lifted or elevated.

The invention comprises further features and combination of parts, hereinafter set forth, shown in the drawings and claimed.

In the drawings:—Figure 1 is a perspective view illustrating the grappling device 40 as applied to the outside of a box, whereby the same may be lifted or elevated. Fig. 2 is a view similar to Fig. 1, showing the grappling device arranged in order to engage the inner side walls of a box, so that 45 the same may be elevated. Fig. 3 is an enlarged view of the grappling device removed from the box, and illustrating the extensible members differently adjusted. Fig. 4 is a longitudinal section view on line 4—4 50 of Fig. 3.

Referring to the drawings, 1 and 2 designate the extensible members or bars, which are arranged in parallel relation, so as to slide with regard to one another. One end 55 of each extensible member or bar is provided with overhanging lugs or hooks, 3

and 4, which engage over the adjacent extensible member or bar, thus acting as guiding means, when the extensible members are adjusted. To hold the extensible members 60 in adjusted positions, one of them is provided with a plurality of apertures 6, which are designed to be engaged by the lug 7 of a spring member 8 carried by the opposite extensible member or bar. This lug 7 also 65 extends through an aperture 9 of the member or bar which carries the spring member, so as to reach and engage any one of the plurality of apertures of the other member. The lug 7 protrudes through the spring 70 member far enough to receive a ring 10, as shown in the drawing, whereby the spring member may be actuated so as to withdraw the lug from any one of the plurality of apertures, whereby the bars or members may 75 be adjusted.

The outer ends of each extensible member or bar are formed with apertures 11, in which the transverse portions 12 of the grappling members are swivelly mounted. To hold the transverse portions in proper relations with regard to the extensible members or bars, cotter pins 13 are provided, which are extended through the transverse portions of the grappling members 85 14.

The grappling members comprise single metal rods, which are bent to form at one of their ends rectangular loops 15, while the other ends are terminated into curved 90 downwardly extending grappling points 16, which are designed to engage a box or other commodity as shown in Fig. 1. On examining Fig. 1 of the drawings it will be seen that as a pulling action is exerted upon 95 the rectangular loops, the grappling points will be thrown inwardly toward the box, in order to securely grip the same, whereby it may be lifted or elevated. It will be seen that as the box or other commodity increases in weight, the gripping action will be correspondingly increased. Upon referring to Fig. 2 of the drawings it will be observed that the grappling members are arranged so that the grappling points may 100 engage the inner walls of the box, thus making it possible to elevate an open box as well as a closed one. To reverse the grappling points from that shown in Fig. 1 to grapple a box by engaging the inside thereof, the 110 grappling members are rotated partially upon their swivels, and the entire grappling

device is reversed end for end, as will be understood upon examining Figs. 1 and 2.

From the foregoing it will be noted that there has been provided a novel form of grappling device comprising extensible members, including reversible grappling devices. In practical fields this device has been found to be exceedingly useful for elevating or lifting piano boxes and the like. Furthermore it has been found to be practicable in every respect.

10 The invention having been set forth, what is claimed as new and useful is:—

15 In a grappling device, a pair of bars constructed and arranged to be adjusted longitudinally with relation to one another, a pair of reversible grappling members constructed of single pieces of rod material, each member having an elongated horizontal 20 portion extending transversely through one end of each bar with devices penetrating the portion one upon each side of the bar to hold said portion swivelly mounted therein, one

end of said horizontal portion having a downwardly extending portion terminating in a right-angled grappling point adapted to engage a box, while the other end of said horizontal portion is provided with a right angle extension disposed in a plane at right angles to the downwardly extending portion, said extension terminating in a loop, said loop and the extension are arranged and movable in a plane offset from the bars so that the grappling point may be reversed and adapted to engage either the outside or inside of the box, the downwardly extending portion and the grappling point being offset from the bars so as to be reversed.

25 30 35 In testimony whereof I have signed my name to this specification in the presence of two subscribing witnesses.

40 WILLIAM O. PECK.
